UNITED STATES PATENT OFFICE.

ANTONIO M. GARCIA, OF STOCKTON, CALIFORNIA.

FINE-GOLD-SAVING DEVICE.

Application filed October 26, 1925. Serial No. 64,791.

This invention relates to improvements in hydraulic mining apparatus, and particularly to a device for saving fine gold and other precious metals from black sand and similar fine materials.

Sand of this kind is found in large quantities in various sections of this State and frequently contains a goodly quantity of free gold. Some of this gold is in the form of particles of appreciable size, which may be reclaimed from the sand by ordinary washing methods. By far the greater percentage of the gold in the sand however is in the form of particles of almost minute size, which heretofore the operators have been unable to segregate from the sand in a commercially practicable and economical manner.

The principal object of my invention therefore is to provide a device for treating sand of this character in such a manner that I may save the greater portion, if not all, of the gold in the sand in a cheap, rapid and efficient manner. The present structure also represents an improvement over a portion of the structure shown in my Patent No. 1,544,272, dated September 22nd, 1925.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of the device.

Fig. 2 is a sectional elevation of the same.

Referring now more particularly to the characters of reference on the drawings, the numeral 1 denotes a sluiceway preferably elevated from the ground somewhat and supported at a suitable height by a trestle-work 2 or the like. This sluice is set at a downward slant so that water will flow freely from its upper to its lower end. Associated with the sluiceway at the upper end thereof is a feed structure (not shown) which is preferably of the same character as that shown in the above mentioned patent. The lower end of the sluiceway discharges into a two-compartment hopper 3, also as shown in said patent.

A certain distance from its upper end the

bottom of the sluice is formed as a removable screen 4 having a mesh of sufficient fineness to only permit of black sand passing therethrough. Beyond the screen the bottom of the sluice has transverse riffles 5 of ordinary character to catch any gold present in the coarse gravel or sand passing down the sluice and of a size incapable of passing through the screen 4.

Mounted under the sluice and having water tight connection therewith is a receptacle 6. This receptacle commences adjacent the upper end of the screen 4 and extends downwardly a certain distance therebeyond. The bottom of the receptacle is preferably parallel to the bottom of the sluice and its lower end is formed as a curved portion sloping upwardly and forwardly to a junction with the bottom of the sluice.

Mounted in the receptacle 6 on guides 7 disposed just under the floor of the sluice beyond the screen 4 are vertically spaced screens 8 of very fine mesh which extend from the bottom end of the screen 4 to a point adjacent the lower end of the receptacle. These screens are slidably mounted in place and are removable from the receptacle for the purpose of enabling any deposit of gold thereon to be readily removed. Said screens are preferably removable from one side of the receptacle and in order to prevent unauthorized removal of the same, the screen frames are provided with orificed lugs 9 on their outer faces to cooperate with a similarly orificed plate 10 on the side of the receptacle so that a padlock or other locking means may be attached to the lugs and plate to maintain the screens locked against removal.

A valved drain outlet 11 is provided in the side of the receptacle adjacent the bottom and lower end thereof so as to enable the water to be drawn off when desired.

The bottom of the sluice from the lower end of the screen 4 to the lower end of the receptacle is preferably made in the form of a removable plate as shown at 12. This enables sand to be shoveled out from the receptacle from above after the screens 8 have collected the gold in the sand and have been removed.

In operation the material from which the gold is to be extracted, including coarse sand, gravel and black sand, is fed onto the upper end of the sluice in conjunction with a certain amount of water. The coarse

material passes down the sluice to the hopper 3, any coarse gold being caught by the rifles 5.

Any fine black sand, and of course fine particles of gold intermingled therewith, together with some of the water, pass down through the screen 4 into the receptacle 6 and tend to move toward the lower end thereof. The water remaining on the sluice and flowing over and past the screen 4 induces an outflow from the receptacle at the lower end of said screen. This in turn causes a longitudinal current of water to be set up in the receptacle from the lower end thereof past the screens 8, and also induces a tendency to vacuum in the pocket A formed at the lower end of the receptacle 6 by the bottom and the curved lower end portion thereof.

The result is that the water and sand in the lower portion of the receptacle are maintained in an agitated condition, causing a froth to be formed adjacent the upper surface of the water in the receptacle and under and between the screens 8. This froth contains fine gold from the sand, which by reason of the agitation set up penetrates through the screens and is deposited thereon.

When an undue amount of sand has collected in the receptacle the flow of water down the sluice is temporarily halted. The water in the receptacle is then drained out by opening the outlet 11 and the sand in passing out through said outlet is removed by first removing the screens 8 and plate 12 as before described, which operation of course exposes the receptacle from above and allows shoveling operations to be readily carried out. This sand may if necessary be further treated if it is felt that it still contains sufficient gold to make a further treatment worth while.

Though I have specifically mentioned gold as being the metal to be saved, this term is presumed to include any other precious metals, such as platinum, silver or the like.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do

not form a departure from the spirit of the invention, as defined by the appended claims.

Having thus described my invention what I claim as new and useful and desire to secure by Letters Patent is:

1. A precious metal saving device comprising a downwardly slanting sluiceway, a screen forming a portion of the bottom thereof, a receptacle having watertight connection with the sluiceway disposed below the same and extending from under the screen to a point beyond the same in the direction of the lower end of the sluice, and superimposed fine-mesh screens mounted in the receptacle adjacent the top thereof and in the area beyond the sluiceway screen.

2. A precious metal saving device comprising a downwardly slanting sluiceway, a screen forming a portion of the bottom thereof, a receptacle having watertight connection with the sluiceway disposed below the same and extending from under the screen to a point beyond the same in the direction of the lower end of the sluice, and a screen mounted in the receptacle adjacent the top thereof beyond the sluiceway screen; the lower end of the receptacle sloping upwardly from the bottom thereof toward the sluiceway screen and terminating adjacent the lower end of the receptacle screen.

3. A precious metal saving device comprising a downwardly slanting sluiceway, a screen forming a portion of the bottom thereof, a receptacle having watertight connection with the sluiceway disposed below the same and extending from under the screen to a point beyond the same in the direction of the lower end of the sluice, whereby when water is flowing down the sluiceway over the screen and into the receptacle an outward flow of such water from the receptacle will be induced at the lower end of the screen and a longitudinal current flowing toward said lower end of the screen from the lower end of the receptacle will be set up in the latter adjacent the top thereof, and screening means for catching precious metal particles disposed in the receptacle in the path of flow of such current.

In testimony whereof I affix my signature.

ANTONIO M. GARCIA,
